Primary Examiner — Michael A Maharajh

(57) **CLAIM**

The ornamental design for a massage shoulder strap, as shown and described.

DESCRIPTION

FIG. 1 is a front, left, bottom perspective view of a massage shoulder strap showing my new design;

FIG. 2 is a back, right, bottom perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is an enlarged view of the encircled area 9 of FIG. 1;

FIG. 10 is an enlarged view of the encircled area 10 of FIG.

1;

FIG. 11 is an enlarged view of the encircled area 11 of FIG.

1;

FIG. 12 is an enlarged view of the encircled area 12 of FIG.

2;

FIG. 13 is an enlarged view of the encircled area 13 of FIG.

2; and,

FIG. 14 is an enlarged view of the encircled area 14 of FIG.

4.

1 Claim, 13 Drawing Sheets
